UNITED STATES PATENT OFFICE.

JOHN C. DUPEE, OF CHICAGO, ILLINOIS, ASSIGNOR OF ONE-HALF TO RIPLEY J. WHITE, OF SAME PLACE.

ACETYLENE-GAS GENERATOR.

SPECIFICATION forming part of Letters Patent No. 592,084, dated October 19, 1897.

Application filed December 21, 1896. Serial No. 616,392. (No model.)

To all whom it may concern:

Be it known that I, JOHN C. DUPEE, of Chicago, in the county of Cook and State of Illinois, have invented certain new and useful 5 Improvements in Acetylene-Gas Generators; and I do hereby declare that the following is a full, clear, and exact description thereof, reference being had to the accompanying drawings, and to the letters of reference marked thereon, which form a part of this specification.

This invention relates to an improved apparatus for generating from calcium carbide the gas known as "acetylene" gas.

The present invention relates to apparatus 15 of this character of that class illustrated in a prior application for patent filed by me August 29, 1896, Serial No. 604,248, and wherein the calcium carbide is held in a generating-chamber provided with a water-inlet opening 20 at its bottom and a source of water-supply is provided from which water is fed to said opening through a regulating-valve which controls the flow of water therethrough.

The invention consists in the matters hereinafter described, and pointed out in the appended claims.

In the accompanying drawings, illustrating 30 my invention, Figure 1 is a view in central vertical section of a gas-generator embodying my invention as applied to a bicycle-lamp. Fig. 2 is a section of the carbide-receptacle and water-tank separate from other parts, taken on line 2 2 of Fig. 1. Fig. 3 is a bottom view of the calcium-carbid receptacle or generating-chamber. Fig. 4 is a view in side elevation of an inner lining placed within the generating-chamber to contain the calcium carbide. Fig. 5 is a detail section taken on line 35 5 5 of Fig. 1.

As shown in the said drawings, A is the gas-generating chamber which is intended to contain the calcium carbide, the same being made preferably of cylindric form.

B is a water receptacle or tank which is attached to the chamber A and, as herein shown, extends around the sides and bottom of said chamber. The bottom of the said chamber

A extends nearly to the bottom of the water-receptacle B, and in the bottom wall a of said chamber is formed an inlet-opening a', which is controlled by a valve-plug d and through

which the water within the receptacle B may enter the bottom of the generating-chamber. Said opening a' is herein shown as formed in a circular plate or disk a², which is somewhat 55 thicker than the bottom wall a' and is secured in a hole in the latter by solder or like means, the thickness of said disk bringing its top surface above the level of the bottom wall of the chamber. The disk a² is used to form 60 a seat for the valve-plug, but the special arrangement of these details illustrated is not essential and a suitable seat for the valve may be otherwise provided. The top of the chamber A is closed by means of a cover A', 65 which is secured thereto in the instance shown by means of a marginal flange a⁴ on the cover which has screw-threaded engagement with a ring a⁵, attached to the upper margin of the chamber.

To the upper part of the side wall of the chamber A is secured a discharge pipe or tube C, which extends downwardly through the water-receptacle B to a point near the bottom of the same and is there carried outwardly 70 through the wall of the receptacle and is connected with a burner-pipe C', which extends outwardly from the receptacle and is then bent upwardly and terminates in a burner c. The water-receptacle B is shown in this instance as secured to the generating-chamber A by means of a flange b at the upper margin of the water-chamber which fits closely against the side wall of the generating-chamber and is attached thereto by solder or like 80 means. The bottom wall b' of the water-receptacle is located a short distance below and parallel with the bottom wall of the generating-chamber and attached to said wall b' is a hub b², through which passes a vertical screw-threaded valve-stem D, having at its upper end the valve-plug d, which is of conical form and is adapted to fit within and close the opening a', these parts constituting a valve 85 of the form commonly known as a "needle-valve." The valve-stem D is provided at its lower end with a milled head d', by which it may be turned for operating the valve.

On the bottom of the generating-chamber is formed an annular, downwardly-projecting 90 flange E, which rests upon the bottom of the receptacle B, but is provided with a series of

- notches e , forming openings through which the water flows in its passage from the water-receptacle to the generating-chamber. Said flange E is conveniently formed by bending 5 or swaging the sheet-metal bottom of the receptacle, so as to form a projecting head or ridge on its under surface. In connection with said flange E , the bottom wall of the water-receptacle is shown as provided with a 10 groove or depression b^3 , which receives the lower edge of said flange E and thereby serves to hold the bottom of the generating-chamber centrally within the water-receptacle and to thereby positively retain the opening a' accurately in alignment with the valve-stem D . 15
- F indicates a filling-orifice formed in the upper part of the water-receptacle and provided with a screw-plug F , by which said filling-orifice is kept normally closed. Said 20 screw-plug is shown as made hollow and as provided with a small air-passage f' , so arranged that when the screw-plug is turned outwardly air will be free to enter the receptacle through said passage.
- 25 In the side of the generating-chamber near its top is formed a passage g , which is controlled by a valve consisting of a valve-seat g' and a valve-plug G . Said passage, when the valve is open, serves to establish connection between the upper part of the generating-chamber and the top of the water-receptacle. The purpose of this passage is to admit the pressure of the generated gas to the top of the water, so as to enable the water to 30 flow freely through the inlet-opening at the bottom of the generating-chamber by preventing the formation of a vacuum in the closed water-receptacle.
- 35 In the particular construction illustrated, 40 the valve-plug G is formed on the end of a screw-threaded shaft G' and has screw-threaded engagement with a tube which fits within a tubular seat g^3 , which extends through the wall of the receptacle and is secured to the 45 generating-chamber at its inner end, said tube having the valve-seat g' formed near its inner end and having adjacent to said seat a lateral exit g^4 , through which the gas escapes to the water-receptacle when the valve is 50 turned backwardly away from the seat.
- 55 Within the generating-chamber A is located a lining or jacket II , the same being shown in exterior view in Fig. 4. Said lining or jacket is made of sheet metal and consists of a cylindric wall II' and perforated bottom and top walls II^2 and II^3 , the latter being, as herein shown, provided with marginal flanges which fit over or embrace the end margins of the cylindric wall. Said cylindric 60 wall is preferably made imperforate except for an annularly-arranged series of openings h^2 , extending around the same some distance below its top. As a special feature of construction constituting a separate improvement the said cylindric wall is provided with disconnected edges which are joined merely by means of interlocking slots and tongues

$h h'$, which engage each other in such manner that when the ends or heads $II^2 II^3$ are removed the meeting edges of the side wall may 70 be easily disconnected and spread apart, the purpose of this construction being to permit the convenient removal of the calcium carbide which is placed within said jacket. In this connection it is to be understood that 75 the calcium carbide is commonly found to be packed so closely in the generating-chamber after it has been acted upon by the water as to be removed from such chamber with difficulty, and only by the use of a tool by which 80 it may be dug or scraped out. Obviously by providing a separate jacket within the generating-chamber, and making the same of a cylinder which may be easily opened or expanded, a means is provided for easily and 85 quickly releasing and removing the closely-packed calcium carbide. Connected with the bottom wall II^2 of said jacket II is a central perforated tube II^4 , which rises to the top of the jacket and passes through a central hole 90 in the top wall II^3 . Said perforated tube II is filled by a mass I of porous material, such as chemists' filter-paper, the same in the instance shown being rolled to form a solid cylinder or plug which is inserted in said tube 95 II^4 and fills the same from top to bottom. In the bottom of the generating-chamber between the bottom wall thereof and the perforated bottom II^2 of the jacket is located a layer J of porous material which may also 100 consist of chemists' filter-paper. It is to be understood, however, that the mass I and layer J may be made of any other porous material having the same general characteristics as filter-paper.

105 The cover A' of the generating-chamber is shown as provided with a safety-valve K , the same consisting of a tubular plug k , secured in the cover and having a central orifice and a conical valve-seat at its upper end, and a valve-plug k' , which fits in said seat and is provided with a depending stem k^2 , around which is placed a coiled spring k^3 , which is confined between the plug k and a shoulder or cross-pin at the lower end of said stem. 110 The purpose of said safety-valve is to permit the escape of gas in case the same shall accumulate so rapidly as to produce a dangerous pressure. Said cover is shown as provided with an inner lining or layer L of 115 leather, rubber, or like material the margins of which form a packing between the cover and the ring a^2 . Said cover is also provided with an inner porous lining M , which serves to absorb any moisture which may accumulate 120 on the under side of the cover and thus prevent the same from dripping upon the dry calcium carbide and thereby unduly increasing the amount of gas generated.

125 The parts above described constitute the generator proper, but I have shown in Fig. 1 an attaching-arm N as secured to the side wall of the water-receptacle and an annular support or base O as secured to the bottom

of the same. I have also shown a reflector P as arranged to surround the burner c, said reflector being inclosed in a cylindric housing P¹, attached to the side of the water-receptacle and adapted to receive and hold said reflector. The reflector is shown as provided with a chimney p and the housing P as provided with an inclosing cap P², which surrounds said chimney and is provided with lateral perforations for the escape of products of combustion. In front of the reflector P is located a glass or lens Q, the same being held in a separate holding-ring Q', that is fitted within a marginal flange P³, formed on the outer part of the housing P. The ring Q' is shown as consisting of outer and inner annular sheet-metal parts q q', the outer part having an internal flange at its inner margin, against which the glass rests, and the inner part fitting within the outer part and bearing at its inner margin against the glass, so as to hold or confine the same in place. The ring Q' is not made to fit closely within the flange P³, but the outer annulus q of said ring is provided with transverse grooves or flutings q², Fig. 5, located at intervals around the periphery of the ring and forming projecting ribs that separate the ring from the inner surface of the flange P³ and thereby form an annular space or opening between the body of the ring and the flange P³. Said annular space serves to admit the outer air to the front of the reflector and thereby serves to keep the glass cool and afford an additional supply of air to the burner.

In preparing the generator for operation, the porous material J is first inserted in the generating-chamber and the jacket H is then filled to the desired extent with calcium carbide, the tube I having been previously packed with a porous mass I. The perforations N serve merely to indicate the quantity of calcium carbide necessary for a charge, and perform no special function in the operation of the apparatus. The jacket is then inserted within the generating-chamber through its open upper end and the cover A' then secured to the chamber. The receptacle B having been filled with water, the generator is in condition for operation. The needle-valve at the bottom of the chamber will preferably be closed before the water is inserted. Upon opening said valve water from the receptacle will immediately begin to pass into the generating-chamber and will be taken up or absorbed by the mass of porous material and also by the layer J thereof and will be carried by said porous material into contact with the calcium carbide, which rests against the perforated tube H¹ and the bottom H² of the jacket, the water passing through the perforations of said parts in an obvious manner. As the water comes into contact with the calcium carbide gas will be generated, and such gas rising through the dry calcium carbide will accumulate in the top of the generating-chamber and escape from the same

to the burner. The porous mass I and layer J have the effect of spreading or distributing the water by capillary action, so as to bring it into contact with a relatively large area of the calcium carbide at once. At the same time the porous material will limit or control the quantity of water carried to the calcium carbide, so as to afford equality of action in the generation of the gas. The porous mass I not only acts to afford uniform distribution of the water but also to carry the water upwardly to the material in the upper part of the generating-chamber. At the beginning of the operation of the generating it is usually desirable to admit a small quantity of air to the water-receptacle by loosening the screw-cap f, this being necessary to permit the water to flow freely to the generating-chamber before the generation of gas begins. As soon as the device is started, however, the air-valve is closed and the gas-valve G will be opened and pressure of gas will be maintained on the water sufficient to insure its continuous and uniform flow to the generating-chamber and thereby making unnecessary the presence of an air-inlet opening to prevent the formation of a vacuum.

I claim as my invention—

1. An acetylene-gas generator comprising a gas-generating chamber provided with a water-inlet opening in its bottom wall, a source or means of water-supply connected with said opening, a perforated tube located in the said chamber above said opening and a mass or filling of porous material within said tube for conveying the water by capillary action into contact with the calcium carbide which surrounds said tube.

2. An acetylene-gas generator comprising a water-receptacle, a gas-generating chamber provided with a water-inlet opening in its bottom communicating with the water-receptacle and provided with a regulating-valve, a gas-delivery pipe leading from the top of the generating-chamber to the burner, and a gas-passage provided with a controlling-valve connecting the top of the generating-chamber with the top of the water-receptacle, said water-receptacle being closed to the external air and having no opening except those connecting it with the bottom and top of the generating-chamber.

3. An acetylene-gas generator comprising a gas-generating chamber having a water-inlet opening in its bottom, a source of water-supply connected with said opening and a perforated tube, located in the chamber and forming an annular space for calcium carbide between the same and the wall of the chamber, said tube being provided with a filling of porous material by which water is conveyed from the inlet-opening to the calcium carbide in contact with said perforated tube.

4. An acetylene-gas generator comprising a generating-chamber having a water-inlet opening in its bottom, a source of water-supply connected with said opening, and a cylin-

- dric jacket adapted for insertion within said chamber, said jacket comprising a cylindric wall which is separable or open at its side to permit the removal of spent carbid of calcium therefrom.
5. An acetylene-gas generator comprising a gas-generating chamber having a water-inlet opening in its bottom, a source of water-supply connected with said opening and a jacket 10 adapted for insertion within the chamber said jacket comprising a cylindric side wall which is separable or open at its side, and flanged bottom and top walls, adapted to hold the side wall in cylindric form.
- 15 6. An acetylene-gas generator comprising a gas-generating chamber having a water-inlet opening in its bottom, a source of water-supply connected with said opening, and a jacket adapted for insertion in said chamber, said 20 jacket consisting of a cylindric side wall, and perforated bottom and top walls.
7. An acetylene-gas generator comprising a gas-generating chamber having a water-inlet opening in its bottom, a source of water-supply connected with said opening, and a jacket 25 adapted for insertion in said chamber, said jacket consisting of a cylindric side wall, a porforated bottom wall and a central perforated tube rising from the bottom wall.
8. An acetylene-gas generator comprising a 30 gas-generating chamber having a water-inlet opening in its bottom, a source of water-supply connected with said opening, and a jacket adapted for insertion in said chamber, said jacket consisting of a cylindric side wall, a 35 perforated bottom wall, a top wall, and a central perforated tube extending between the bottom and top walls.
9. An acetylene-gas generator comprising a gas-generating chamber having a water-inlet 40 opening in its bottom, a source of water-supply connected with said opening, and a jacket adapted for insertion in said chamber, said jacket consisting of a cylindric side wall, a 45 perforated bottom wall, a top wall and a central perforated tube extending between the bottom and top walls, said side wall being separable at one side and the bottom and top walls being flanged to engage the ends thereof.
- In testimony that I claim the foregoing as 50 my invention I affix my signature, in presence of two witnesses, this 9th day of December, A. D. 1896.
- JOHN C. DUPEE.
